CLAIM

The ornamental design for a faucet, as shown and described.

DESCRIPTION

FIG. 1 is a side perspective view of a faucet design;
FIG. 2 is a bottom perspective view thereof;
FIG. 3 is a top view thereof;
FIG. 4 is a left side view, which is a mirror image of the right side view thereof;
FIG. 5 is a bottom view thereof;
FIG. 6 is a front view of thereof; and,
FIG. 7 is a rear view of thereof.

The broken lines shown represent unclaimed subject matter and form no part of the claimed design.
